 Siegmar-Schonau, Germany, assignors to Kalio,
 Inc., New York, N. Y.

Application August 12, 1939, Serial No. 289,896
 In Germany August 20, 1938

3 Claims. (Cl. 66—187).

This invention is intended to improve a known method of manufacturing stockings having a full fashioned or French foot wherein a stocking is entirely completed on one and the same flat knitting machine, so that in order to get a stocking in its finished shape it is but necessary to make its longitudinal seam.

Stockings of this kind are denoted as single seam stockings and they were hitherto manufactured in that way that after the leg had been finished, the middle portion needles were brought up to rest, the heel portions were joined to the high heel ones, the loops of the heel courses, after a certain number of the latter having been made, were widened outwardly and at the same time the antecedent innermost marginal loops of the heel courses having been already worked upon were picked up by the knitting needles which became vacant. This results in the innermost marginal loops of the heel portions being carried on those knitting needles which are disposed adjacent the middle portion of the needle head whereafter the foot portion may be joined to the said marginal loops and to the middle portion of the leg.

For the purpose of bringing up the marginal loops of the already worked courses of heel loops a particular narrowing device is necessary having for each heel portion a part adapted to swing through an angle of 90°. Such a particular arrangement of the narrowing device may be avoided, in accordance to a modification of the known method, thereby that the inner marginal loop of each heel course is left immediately after having been formed on the corresponding knitting needle, said latter being then brought up to rest. In this way the inner marginal loops of the heel courses are positioned, after said courses are finished, on those knitting needles which are adjacent the middle portion of the needle head, and the foot may be now joined to said marginal loops and to the middle portion of the leg.

Instead of a single marginal loop, one may leave also a number of them adjacent the margin on the corresponding knitting needles which are then brought up to rest. Further it is not necessary to leave the marginal loops of each consecutive heel course, but it may be sufficient to have the marginal loops of every second, third or fourth heel course, etc., left on the knitting needles and then to bring the latter to rest.

A constant breadth of the heel portions is obtained by narrowing the loops which do not remain for the time being on their needles or in that way that an equal number of needles corre-

sponding to the number of inner needles brought up to rest are set to participate outwardly in the knitting operation.

Owing to the widening or addition of loops on the outer ends of the heel courses, a tension is created in the heel portions which manifests itself unfavourably in the finished stocking. In order to exclude the influence of said tension on the shape of the stocking we are proceeding so that after an arbitrary but relatively small number of heel loop courses have been made, there are repeatedly carried out courses passing through the heel portions and through the middle portion of the leg. These latter courses provide for a relieving of the tension in the heel portions.

Henceforward an improved method of manufacturing stockings according to our invention is disclosed with reference to the appended drawings in which:

Figures 1, 2 and 3 illustrate steps of manufacturing a stocking with a French foot by our improved method.

Fig. 4 indicates the location of the through-loop courses, and

Fig. 5 is a fragmentary view of a finished stocking.

With reference to Fig. 1, first of all a leg 1 is manufactured in a usual manner up to the line $a-b-c-d-e-f$. Herein section $c-d$ corresponds to the end loops of the leg middle portion. Sections $a-b$ and $e-f$ represent the high heel end courses.

After the leg is finished, the part of the needle head corresponding to section $c-d$ is brought up to rest, and the heel portions $a-a_n-b_n-b$ and $e-e_n-f_n-f$ are joined respectively to the end courses $a-b$ and $e-f$. The operation is carried out in the manner represented on Fig. 4.

After two courses a_1-b_1 and a_2-b_2 and respectively e_1-f_1 and e_2-f_2 are finished, the inner marginal loops are left on the corresponding knitting needles which are then brought up to rest. In the case of the exemplary embodiment it is assumed that two inner knitting needles are brought up to rest. This may be done in this way that specially formed transfer needles arranged on the narrowing machine take up the pressing of the frame needles and that those of the frame needles which have to be just brought up to rest are not pressed by the transfer needles. During the pressing operation the said transfer needles are positioned in front of the presser edge of the knitting machine. Needles have preferably formed thereon, above their grooves, presser

surfaces shaped as hooks arranged so that the transfer needles remain available for an ordinary narrowing (covering) operation.

For the purpose of preserving a uniform breadth of the heel portions, the loops are either widened in outward direction, or new loops are exteriorly cast on by taking up new knitting needles. In the disclosed exemplary embodiment two knitting needles are exteriorly added. Owing to the widening of loops or respectively by taking up new needles and by simultaneously holding fast the marginal loops there are formed eyelets in the heel portions. However said eyelets are not objectionable to a good appearance of the produced articles, but they may be used as ornamental elements, because of said eyelets not being limited to one and the same column of loops, but being divided in two such columns spaced apart through a distance of one or two loops.

After a next pair of heel courses $a_3-b_3-a_4-b_4$ and e_3-f_3, e_4-f_4 are formed (loop courses e_1-f_1 are not represented in the drawings), the above recited sequence of operative steps are repeated up to course a_8-b_8 and respectively e_8-f_8 . Meanwhile, owing to the widening operation and/or by taking up new loops, a substantial tension has arisen in the heel portions, said tension acting rather diagonally. The position of the knitted article on the needle head represented on Fig. 4 is not quite as in reality, the purpose being to render the figure more demonstrative. In reality, the marginal loops of alternate heel loop courses are also located on knitting needles lying in the same rows as the knitting needles of loop courses a_8-b_8 and respectively e_8-f_8 . Therefore the heel portions are assuming a somewhat creasy conformation as it may be seen from Fig. 2.

In order to moderate, or respectively to remove, the influence of tension on the shape of a finished stocking, we form in conjunction with the course a_8-b_8 and respectively e_8-f_8 a through course $a_9-b_9-c_1-d_1-e_9-f_9$ which may be denoted as a relieving one. It is to be understood that a number of consecutive relieving courses also may be formed. Generally speaking, satisfactory results are obtained if one relieving course is provided after eight heel courses, as represented on Fig. 4. As it is shown on Fig. 4, after eight further heel courses there is again provided one relieving course $b_{18}-c_2-d_2-e_{18}$. The figure represents also in conjunction a part of two heel courses having inner marginal loops $b_{19}-b_{20}$. At this moment those of the loops among the represented ones are carried by the needles of the frame needle head which are particularly denoted by the addition of small circles. After the production of a relieving course, those marginal loops of heel courses which were previously carried on needles brought up to rest are no more present on said

needles, but as follows from the representation of needles, they are replaced by those loops of the relieving course which have been made on said needles. In other words, during the production of a relieving course, also those needles which have been previously brought up to rest are compelled to cooperate in the formation of loops. Finally there are thus present on needles brought up to rest, in correspondence with sections $b-b_n$ and respectively $e-e_n$, those loops which belong to the last relieving course.

Fig. 2 illustrates the leg with added heel portions carried in needles of the head after the last courses a_n-b_n and respectively e_n-f_n have been entirely or partly drawn off the knitting needles. In conjunction therewith a foot is made, so that there is formed a stocking corresponding to Fig. 3 and having but a single seam. As shown on Fig. 5, the relieving courses form an inserted wedge A, B, C to each side of the leg and foot middle portion.

We claim:

1. The method of forming the heel portions of a stocking blank which comprises knitting heel courses of substantially uniform width while holding the terminal loops of the wales forming the instep portion of the fabric, discontinuing knitting and holding the terminal loops of successive wales adjacent said instep portion of the fabric during the formation of following heel courses, and interposing between selected heel courses a full course of loops extending across both heel portions and across the instep portion of the fabric.
2. The method of forming the heel portions of a stocking blank which comprises knitting heel courses while holding the terminal loops of the wales forming the instep portion of the fabric, discontinuing knitting and holding the terminal loops of successive wales adjacent said instep portion of the fabric during the formation of following heel courses, extending said heel courses successively outwardly to maintain a substantially constant width of heel fabric, and between pre-selected numbers of heel courses interposing a full course extending across the heel portions and instep portion of the fabric.
3. A stocking blank comprising a leg portion, heel portions comprising each a number of heel courses of substantially equal width, the innermost loop of each of certain succeeding heel courses forming the terminating loop of an adjacent wale outwardly considered from the middle portion of the leg, and a foot portion comprising instep courses connected by knitting to said innermost wale terminating loops, and including an interposed course or courses passing through both heel portions and through the middle portion of the leg.
